(57) **CLAIM**

The ornamental design for a battery-powered goggle, as shown and described.

DESCRIPTION

FIG. 1 is a perspective view of a battery-powered goggle showing my design. The broken lines showing the battery-powered goggle strap in FIG. 1 are for illustrative purposes only and form no part of the claimed design;

FIG. 2 is an alternate perspective view of the battery-powered goggle of FIG. 1. The broken lines showing the battery-powered goggle strap in FIG. 2 are for illustrative purposes only and form no part of the claimed design;

FIG. 3 is a front elevation view of the battery-powered goggle of FIG. 1;

FIG. 4 is a right side elevation view of the battery-powered goggle of FIG. 1. The broken lines showing the battery-powered goggle strap in FIG. 4 are for illustrative purposes only and form no part of the claimed design. A left side elevation view has not been included but is the opposite, mirrored, view of FIG. 4;

FIG. 5 is a top elevation view of the battery-powered goggle of FIG. 1; and,

FIG. 6 is a bottom elevation view of the battery-powered goggle of FIG. 1.
